UNITED STATES PATENT OFFICE.

JESSE A. B. SMITH, OF STAMFORD, CONNECTICUT, ASSIGNOR TO UNDERWOOD TYPE-WRITER COMPANY, OF NEW YORK, N. Y., A CORPORATION OF DELAWARE.

TYPEWRITING MACHINE.

Application filed March 3, 1924. Serial No. 696,556.

To all whom it may concern:

Be it known that I, JESSE A. B. SMITH, a citizen of the United States, residing in Stamford, in the county of Fairfield and State of Connecticut, have invented certain new and useful Improvements in Typewriting Machines, of which the following is a specification.

This invention relates to typewriting machines, and particularly to a continuous web typewriting machine, including means for controlling a record-web to receive a condensed record of matter typed on the successive forms that are printed on a work-web.

In some classes of continuous billing work, it is desirable to provide a condensed record or tally on which there appear only the names of the customers to whom the bills are sent. Accordingly provision is made whereby only the first line of each bill is printed through onto the record-web; and, in order that such entries on the record-web may be closely arranged, the record-web is caused to progress only one line-space for each bill that is written. The present invention provides a machine for doing this class of work quickly and efficiently. The invention is not limited, however, to the typing of a single line of each bill onto the record-web, nor to the typing of the line or lines at the head of the bill onto the record-web.

In the preferred form of the invention and as herein illustrated, provision may be made in a continuous billing type-writing machine of the displaceable platen type, such, for example, as the machine disclosed in the patent to Wernery & Smith No. 1,132,055, of tally or record-web mechanism including a tally and carbon supply-controlling means at the introductory side of the machine and a tally and carbon take-up roll mounted on the displaceable platen-frame of the machine at the delivery side of the platen. A shield is carried by the carbon-carrier between the tally-sheet and its carbon to cover all of said carbon except a narrow margin at the forward extremity. When a fresh bill-form is brought to position for typing, the portion of the record-

web carbon in advance of the shield is effective to print on the record-web the matter typed on the bill, but, after the typing of the first line, the shield is advanced by the platen to cover the line of writing. Throughout 55 the further typing of the bill, the record-web is fed by the platen from the rear to the front thereof, but receives no impressions. This feeding creates a slack in the record-web at the delivery side of the platen. 60

Provision is made of means for causing the record-web take-up roll to wind up and firmly hold against unwinding a portion of this slack equal in length to the portion of the record-web which has been typed upon in the writing of the previous bill, and of means for withdrawing the remainder of the slack to the introductory side of the platen when the platen is displaced. 65

To this end, the platen-displacing frame-release handle is arranged, when operated, to engage a record-web line-space slide having a pawl thereon to engage a line-space ratchet-wheel secured to the take-up roll. Said roll is also provided with a locking 70 wheel engaged by a locking pawl to prevent unwinding of the record-web during a carbon-retracting and slack-withdrawing operation.

After the take-up roll has been line-spaced 80 and the platen-displacing frame has been released, the displacing frame may be swung forward to lift the platen from its normal position, to enable the bill-web to be straightened out for the usual purpose of 85 gaging and of facilitating the shifting of the carbon-sheets. The bill-web may then be pulled forward and gaged, and the carbon-carrier may be pushed rearwardly to retract the carbons, the rearward movement 90 of the carbon-carrier being limited by a stop.

In order to condense the entries on the record-web, it is important that the slack portion of the record-web which was fed idly past the printing point during the writing of the bill be retracted to the introductory side of the platen. This slack is taken up by causing the record-web with 95 its carbon to be drawn rearward by the car- 100

bon-carrier during its carbon-retracting movement. For this purpose, there is provided on the carbon-carrier a friction device to drag as a brake against the record-web with sufficient force to cause the record-web to be pulled rearward by the carbon-carrier so long as there is any slack in the web. It will be remembered that the record-web take-up roll was line-spaced prior to the release of the platen-displacing frame to wind up a length of record-web equal to the amount that had been written upon, and that this portion of the web was locked against unwinding by the locking wheel and pawl. When the slack in the record-web has been taken up, the friction device connecting the record-web and the carbon-carrier yields, permitting the carbon-carrier to continue its rearward movement, while the record-web remains stationary. It will be seen that the net result of the line-feeding of the record-web by the platen, the line-spacing of the take-up roll and the retraction of the carbon-carrier, is an advance of the record-web a distance equal to the length of said web that has been written upon.

While the take-up roll line-feeding mechanism is controlled by the displacing-frame-releasing lever, the movement of this lever to line-feed the take-up roll is not necessarily followed by the displacing of the platen-frame, for the releasing lever may be operated again and again until the take-up roll has been line-fed any amount that may be required.

The line-space slide is mounted on the machine-frame while the line-spacing ratchet of the take-up roll is mounted on the displacing frame. There is a possibility, therefore, that the ratchet-wheel may be lifted out of engagement with the line-space pawl before the operative stroke of the pawl is completed. This would tend to make the length of the line-feeding steps uncertain. To overcome this, provision is made of a spring-detent for engaging a toothed wheel fast to the take-up roll to control the length of the feeding steps. In addition to this, a latch is provided on the displacing frame to hold the displacing frame down until the line-spacing operation has been completed. This latch is located to be engaged and moved to ineffective position by the line-space slide at the end of its operative stroke.

In accordance with one feature of the invention, a record-web-supply reel is mounted upon the carbon-carrier of the machine, and the friction device also mounted on the carbon-carrier serves as a brake or drag on the record-web roll to prevent unwinding of the record-web before the slack has been taken up in the retraction of the carbon-carrier. The mounting of the record-web reel on the carbon-carrier is important, because it obviates the creation of objectionable slack at

the introductory side of the machine. The supply-reel moves forward bodily with the carbon-carrier at the line-spacing operation of the platen, so that none of the web carried by it is unwound.

70

Other features and advantages will hereinafter appear.

In the accompanying drawings,

Figure 1 is a longitudinal, vertical section of a part of a continuous billing machine 75 having the present improvements applied thereto, as seen by one looking toward the left end of the machine.

75

Figure 2 is a fragmentary, vertical, longitudinal section, as seen by one looking toward the right end of the machine.

Figure 3 is a plan view of a part of the machine.

Figure 4 is a diagrammatic view illustrating the positions of the parts, particularly 85 the shield, at the writing of the first line on a bill.

85

Figure 5 is a view similar to Figure 4, illustrating the positions of the parts at the conclusion of the writing of a bill.

90

Figure 6 is a view similar to Figure 4, showing the platen-frame displaced preliminary to gaging the completed bill.

90

Figure 7 is a view similar to Figure 4, showing the bill in its gaged position and the carbon-carrier retracted to the point where the unreeling of the record-web begins.

95

Figure 8 is a view similar to Figure 7, 100 showing the carbon carrier fully retracted.

100

Figure 9 is a fragmentary, longitudinal, vertical section showing particularly the means for controlling the take-up roll.

Figure 10 is a detail view showing the 105 detent for the take-up roll, and means for making said detent ineffective.

105

Figure 11 is a detail view showing the locking wheel and locking pawl of the take-up roll, and means for rendering the locking pawl ineffective.

110

Figure 12 is a plan view of the carbon-carrier and the record-web-supply-controlling means constructed in accordance with the preferred form of the invention.

115

Figure 13 is a fragmentary, detail view 115 of the mechanism shown in Figure 12, on a larger scale.

115

Figure 14 is a vertical, longitudinal section of the form of the invention disclosed in Figure 12.

120

The typewriting machine includes types 10 mounted to swing upwardly and rearwardly against the front face of a cylindrical platen 11, journaled by its axle 12 in the ends of a displaceable platen-frame 13. This frame 13 is mounted to swing about stub-shafts 14 on the traveling carriage 15, which moves in letter-feed and return directions upon front and rear rails 16. A rear carriage-extension 17 comprising rails 18 is

125

130

supported at its rear end upon a transverse rail 19, carried by an extension 20 of the machine-frame 21. Work-webs 22 are led into the machine over a rear bar 23, and 5 thence forward between carbon-blades 24 carried by a carbon-carrier 25 that is reciprocable toward and from the platen along the rails 18 of the carriage-extension 17. Carbons 26 extend forward from the carbon-blades 24 between the plies of work-web 22 and are line-fed with the work-web by the platen 11 and co-operating feed-rolls 27. At 10 the completion of a bill, a handle 28 is moved to the rear to move hooks 29 clear of pins 30 on the platen-displacing frame 13, to permit said frame to be swung upward for straightening of the work-webs 22 and retraction of the carbons 26 by movement of the carbon-carrier handle to thrust the carbon-carrier to the rear. When the displacing frame 13 is raised, the work-webs 22 are seized and drawn forward against a leading-edge gage 31 carried by a gage-bar 32 on the displacing frame, and the carbon-carrier 20 handle 33 is thrust to the rear to retract the carbons 26. The displacing frame 13 is then 25 returned to its normal position and the bill-webs 22 are torn off against a knife 34. The mechanism thus far described is like that 30 disclosed in the patent to Wernery & Smith referred to above.

The platen 11 is connected, through gears 35 upon the ends of its axle 12, pinions 36 on the carriage 15 and co-operating gears 35 37 on the carriage, with the usual line-spacing mechanism and with platen-rotating finger-wheels 38, one of which is shown. The arrangement of the gearing 35, 36, 37, to control this connection is the same as that 40 disclosed in the application of William F. Helmond, Serial No. 609,560, filed December 29, 1922; that is to say, the gears 35 leave engagement with the pinions 36 when the platen is displaced and are caused to re- 45 engage the pinions when the platen is lowered.

For providing a condensed record of a portion of the matter written on the bills, provision is made of a record-web-supply 50 reel 39, mounted on brackets 40 carried by the carbon-carrier for reciprocation therewith. This reel may have wound upon it both a record-web 41, and a carbon-web 42 for making impressions upon the record-web. 55 Since it is only the first line of each bill that is to be reproduced upon the record-web 41, it is desired to avoid the printing through to the record-web of any matter after the first line. For this purpose, a flexible shield 43 is mounted on a blade 44 of the carbon-carrier to lie between the record-web 41 and its carbon 42, this shield being adjusted to terminate at its forward extremity a short distance behind the carbons 26 and hence a 60 short distance below the line of writing

when the carbon-carrier is in its fully retracted position. At the writing of a bill, the first line or lines are printed through on the record-web 41 according to the adjustment of the shield 43, but, after this, the 70 writing of the bill proceeds without any impressions being made on the record-web. The record-web 41 and its carbon 42 are fed idly around the platen 11 with the bill-web 22 until the bill has been completed. 75

In accordance with an important feature of the present invention, provision is made at the delivery side of the platen of means for winding up a portion of the record-web 80 equal in length to the portion which has been written upon, and for holding such wound-up portion firmly against unwinding. Such means may comprise a take-up roll 45 mounted in ears 46 extending rearwardly from a plate-like bracket 47, secured to the front paper-table 48 that commonly forms a part of the platen-displacing frame 13. A ratchet-wheel 49 is fast upon the axle 50 of this roll 45, and is arranged to be driven step by step by a pawl 51 pivoted on a line-space slide 52 mounted in a bracket 53 fixed on the carriage 15 of the machine. The line-space slide 52 has an arm 54 arranged in the path of the displacing-frame-release handle 28, the arrangement being such that movement of the release-handle to the rear, preparatory to the lifting of the displacing frame 13, actuates the line-space slide 52 to thrust the pawl 51 to the rear, and thereby feed the ratchet-wheel 49 a tooth-space, winding the record-web 41 onto the take-up roll 45. The line-space slide 52 is returned to its forward position by a spring 55. 95

There is a possibility of the operator's lifting the displacing frame 13 as soon as it is released by the handle 28 and prior to the completion of the line-spacing of the take-up roll 45. In order to prevent this, provision is made of a latch 56 pivoted on the bracket 47 for engaging a locking pin 57 on the bracket 53. This latch has an ear 58 arranged to be engaged by a projection 59 on the line-space slide 52 to move the latch clear of the locking pin 57 at the end of the line-spacing movement of the slide. A spring 60 tends to maintain the latch 56 in engagement with the locking pin 57 and to move the latch forward as soon as it is raised clear of the pin, the forward movement of the latch being limited by engagement of an ear 61 with the bracket 47. In order to enable the latch 56 to reengage beneath the locking pin 57, upon the return of the latch to its lowered position, the lower surface 62 of the latch is beveled, so that the latch may be cammed back by the locking pin and may then snap beneath said pin under the influence of the spring 60. 105

To further assist in controlling the feeding steps of the take-up roll, provision is 110 115 120 125 130

made of a detent-roller 63 to bear against the periphery of a toothed wheel 64 fast on the axle 50 of said roller. This detent-roller 63 is mounted in an arm 65 pivoted at 66 upon the bracket 47 of the displacing frame, and is urged toward the wheel by a spring 67. The detent may be made ineffective, when desired, by means of a cam 68 that engages the lower surface of arm 65 to lift it away from the wheel 64. A finger-piece 69 is connected to this cam 68 for operating it, and is limited in its movement by a notched disk 70 fast to the cam and to the finger-piece and arranged to have the ends 15 of its notch moved into engagement with a pin 71 on the bracket 47.

Provision is also made at the opposite side of the carriage of a locking pawl 72 to engage between the teeth of a locking wheel 20 73 fast on the axle 50 of the take-up roll 45 to prevent retrograde motion of said roll. This pawl 72 is pivoted upon the bracket 47 and is urged toward the locking wheel 73 by a spring 74. Provision is also made for 25 rendering this locking pawl 72 ineffective when it is desired to unwind the completed record-web 41 from the take-up roll 45. A cam 75 may be moved between positions to render the pawl effective and ineffective by 30 a knurled finger-piece 76, the positions of the cam being determined by a pin 77 on the bracket 47 which engages with shoulders 78 on the cam 75.

The take-up roll may also be rotated at 35 any time by means of a finger-wheel 79 fast on the axle 50.

The displacing frame 13 and the mechanism carried by it are braced and in part supported by legs 79^a which extend downwardly and rearwardly from the bracket 47 to rest upon the forward ends of the rails 18.

When a bill is first begun, the carbons 26 and the shield 43 are fully retracted, the shield being located a short distance below 45 the line of writing, as shown in Figure 4.

The first line is then written, and this line is copied through on the record-web because the shield 43 is ineffective. At the subsequent line-spacing of the platen, the shield 43 is fed forward to cover the line of writing, so that subsequent lines written on the bill-web are not reproduced upon the record-web. The typing of the bill proceeds until the bill has been completed, as indicated, for 55 example, in Figure 5. During this typing, the carbon-carrier 25 with the record-web reel 39 is drawn forward toward the platen 11, and the record-web 41 together with the bill-web 22 is line-fed by the platen. The

60 record-web 41 together with the bill-web 22 is line-fed by the platen. The record-web 41 is not taken up, however, by the take-up roll 45, but forms a slack at the delivery side of the platen, as indicated in Figure 5. The 65 platen is then displaced, as shown in Figure

6, after which the bill-web 22 is drawn forward to the gage 31, as shown in Figure 7, and the carbon-carrier 25 is retracted. Movement of the carbon-carrier 25 to the rear, besides retracting the carbons 26, serves 70 to withdraw the record-web slack from the delivery side of the platen until the position of the carbon-carrier shown in Figure 7 has been reached. To assure this mode of operation, a friction brake 80, pivoted at 81, on the carbon-carrier 25, is pressed by a spring 82 into engagement with the periphery of the record-web roll 39, to prevent unreeling of the record-web 41 so long as any slack exists. When all of the slack has been taken 80 up, as seen in Figure 7, the continued rearward movement of the carbon-carrier 25 into engagement with an adjustable stop 83, as seen in Figure 8, is effective to unreel the record-web 41 and the record-web carbon 42. 85

In Figures 12, 13 and 14, the preferred form of record-web-controlling device is shown. The record-web is led from the rear of the machine through a slotted gage bar 84 on the carbon-carrier 25, and thence 90 between clamping bars 85 and 86, the latter of which is provided with rubber feet 87 to exert a frictional drag upon the record-web 41. The shield 43 is clipped to the bar 85. The operation of this form of the invention 95 is like the one already described, the record-web 41 being retracted with the carbon-carrier 25 until all of the slack has been taken up, and then being caused to remain stationary during the farther retraction of 100 the carbon-carrier.

In this preferred form, it will be noted that a commercial form of record-web is employed; that the friction-brake applied to the web at the rear of the platen to retract the slack in the web at the front of the platen, is applied to the record-web and not to the carbon-overlay; and that the carbon for the record-web is secured to and operated by the carbon-carrier in the usual manner and used repeatedly until exhausted. 110

It will be further noted that the displaceable platen-frame not only carries the leading edge gage for the work-plies, but also supports a record-web winding roll and a complete line-spacing mechanism therefor, including a check pawl and a detent to insure accurate line-spacing of the record-web, all of which are displaceable with the platen-frame; that the displaceable frame is normally locked to the carriage by a manually-operable latch; that a rearward swing of said latch to release the platen-frame for a displaceable movement simultaneously operates the line-spacing mechanism of the record-web roll; and that, to prevent the premature displacement of the platen-frame before a full line-spacing movement of the record-web has taken place, a supplemental frame-locking means must 120 125 130

be first released by the record-web line-spacing mechanism.

It will also be noted that the reciprocable carrier has a record-web supply roll mounted thereon; that the same roll supplies carbons for the record-web; that a shield is adjustably secured to the carrier to lie between the record and carbon webs; that the record-web, carbon-web and shield are retractible by the carrier at the end of each typing operation; and that the record and carbon webs are unwound from the supply-roll a line-space dimension at the end of each retractive movement of the carrier.

15 Variations may be resorted to within the scope of the invention, and portions of the improvements may be used without others.

Having thus described my invention, I claim:

20 1. In a continuous billing typewriting machine, the combination with a revoluble platen, a platen-displacing frame and a carbon-carrier reciprocable toward and from the platen, of a record-web and record-web-carbon bearing roll mounted on the carbon-carrier, a shield also carried by the carbon-carrier between the record-web and its carbon, constructed and arranged to prevent the copying through onto the record-web of 25 all matter typed on the work-web except a portion written in a predetermined field longitudinally of the work-web, feed-rolls co-operating with the platen to feed the work-web and record-web together, record-web take-up mechanism at the delivery side 30 of the platen to take up and hold against retraction a stretch of record-web corresponding in length to the length of the record-web field typed upon, and a friction device on the carbon-carrier engaging the record-web to cause the record-web to be drawn to the rear by the carbon-carrier until 35 all of the slack at the delivery side of the platen created by the line-feeding of the record-web by the platen has been taken up, and then to permit the record-web to remain stationary during the further retraction of the carbon-carrier.

40 2. In a continuous billing typewriting machine, the combination with a revoluble platen, a platen-displacing frame, and a carbon-carrier reciprocable toward and from the platen, of a record-web and record-web-carbon bearing roll mounted on the carbon-carrier, a shield also carried by the carbon-carrier between the record-web and its carbon, constructed and arranged to prevent the copying through onto the record-web of 45 all matter typed on the work-web except a portion written in a predetermined field longitudinally of the work-web, feed-rolls co-operating with the platen to feed the work-web and record-web together, record-web take-up mechanism at the delivery side of 50 the platen to take up and hold against re-

traction a stretch of record-web corresponding in length to the length of the record-web field typed upon, and means on the carbon-carrier to cause the slack in the record-web created at the delivery side of the platen by the line-feeding of the record-web with the work-web to be withdrawn to the introductory side of the platen by the retraction of the carbon-carrier.

55 3. In a continuous billing typewriting machine, the combination with a revoluble platen, a platen-displacing frame and a carbon-carrier reciprocable toward and from the platen, of record-web-supply means mounted on the carbon-carrier to travel therewith toward and from the platen, record-web take-up means on the platen-displacing frame at the delivery side of the platen, and means to prevent the withdrawal of the record-web from the web-supply means so long as there is any slack in the record-web between the supply and take-up means.

60 4. In a typewriting machine, a cylindrical platen, work-feeding means co-operating with the platen to feed a work-web together with an underlying record-web and record-web-carbon around the platen from rear to front, means at the delivery side of the platen to take up and hold against retraction a portion of the record-web and its carbon, and means to retract to the introductory side of the platen that portion of the record-web and its carbon not held by the take-up means.

65 5. In a typewriting machine, a cylindrical platen, means co-operating with the platen to feed a record-web around the platen from rear to front together with a superposed work-ply, means to retract the record-web independently of the superposed work-ply, and means to limit the retraction of the record-web.

70 6. In a continuous billing typewriting machine, the combination with a platen-displacing frame, a revoluble platen therein and a carbon-carrier reciprocable toward and from the platen, of a record-web take-up roll mounted on the platen-displacing frame for movement to a position such that the record-web can be substantially straightened beneath the displaced platen, and means connecting the record-web to the carbon-carrier to cause the accumulated slack in the record-web at the delivery side of the platen to be retracted to the introductory side of the platen by the retraction of the carbon-carrier.

75 7. In a continuous billing typewriting machine, the combination with a displaceable platen-frame, a revoluble platen therein and a carbon-carrier reciprocable toward and from the platen, of a set of carbons extending forward from the carbon-carrier to print upon the inside plies of a composite

- work-web, a shield carried by the carbon-carrier to extend forward to within about one line-space of the forward extremities of the carbons to lie between a record-web adjacent the platen and a carbon for printing on the record-web to prevent the reproduction on the record-web of all but the first line typed on the work-web, means co-operating with the platen to feed the work-web and record-web together, a take-up roll for the record-web on the displaceable platen-frame, means for holding the displaceable platen-frame down in writing position, a handle for releasing the platen-frame, line-space mechanism for the record-web take-up roll arranged to be operated by the movement of the platen-frame-release handle, means to lock the record-web on the take-up roll against unwinding, and means on the carbon-carrier for yieldingly gripping the record-web to retract to the introductory side of the platen that portion of the record-web which was line-fed to the delivery side of the platen with the work-web, and which was not taken up by the line-spacing of the take-up roll.
8. In a continuous billing typewriting machine, the combination with a revolute platen, a platen-displacing frame and a carbon-carrier reciprocable toward and from the platen, of record-web-controlling means comprising record-web take-up and holding mechanism carried by the platen-displacing frame.
- 35 9. In a continuous billing typewriting machine, the combination with a revolute platen, a platen-displacing frame and a carbon-carrier reciprocable toward and from the platen, of record-web-controlling mechanism comprising a record-web-winding roll and means for turning the roll independently of the platen to wind the record-web.
10. In a continuous billing typewriting machine, the combination with a revolute platen, a platen-displacing frame and a carbon-carrier reciprocable toward and from the platen, of record-web-controlling mechanism comprising a record-web-winding roll at the delivery side of the platen, line-spacing mechanism for turning said roll step by step independently of the platen to wind the record-web, and a finger-piece rotatable to turn the roll to wind the record-web.
11. In a continuous billing typewriting machine, the combination with a revolute platen, a platen-displacing frame and a carbon-carrier reciprocable toward and from the platen, of record-web-controlling mechanism comprising a take-up roll, means to line-space the take-up roll, detent-means to control the extent of the line-spacing, and locking means to prevent reverse feeding of the take-up roll.
12. In a continuous billing typewriting machine, the combination with a revolute platen, a platen-displacing frame and a carbon-carrier reciprocable toward and from the platen, of record-web-controlling mechanism comprising a take-up roll, means to line-space the take-up roll, detent-means to control the extent of the line spacing, locking means to prevent reverse feeding of the take-up roll, and means to render the detent and locking means ineffective when desired to permit the unwinding of the record-web.
13. In a continuous billing typewriting machine, the combination with a revolute platen, a platen-displacing frame and a carbon-carrier reciprocable toward and from the platen, of record-web-controlling mechanism comprising a take-up roll, feeding means for the take-up roll, locking means for the roll to prevent unwinding of the record-web, and means to disable said locking means when desired.
14. In a typewriting machine, the combination with a revolute platen around which a work-ply and an underlying record-web may be fed, of a record-web take-up roll at the delivery side of the platen, feeding means for the take-up roll, locking means for the take-up roll comprising a locking wheel and a locking pawl to cooperate therewith to prevent unwinding of the roll, and means to disable the locking means comprising a cam to bear against the pawl and a finger-piece to turn the cam.
15. In a typewriting machine, the combination with a revolute platen around which a work-web and an underlying record-web may be fed, of a record-web take-up roll at the delivery side of the platen, feeding means for the take-up roll, comprising a toothed wheel fast to the roll and a spring-detent to bear against the wheel, a cam movable to render the detent ineffective, a handle for operating the cam, and means to limit the movement of the cam to its effective and ineffective positions.
16. In a continuous billing typewriting machine, the combination with a displaceable platen-frame and a revolute platen therein, of a tally-strip take-up roll on the displaceable platen-frame, a hook for holding the displaceable platen-frame in writing position, a handle for moving the hook to release the platen frame, and mechanism operated by the movement of the handle to line-feed the take-up roll.
17. In a continuous billing typewriting machine, the combination with a displaceable platen-frame and a revolute platen therein, of a tally-strip take-up roll on the displaceable platen-frame, a hook for holding the displaceable platen-frame in writing

- position, a handle for moving the hook to release the platen-frame, and mechanism operated by the movement of the handle to line-feed the take-up roll, comprising a line-space slide, a pawl carried by the slide, and a ratchet-wheel fast to the take-up roll to be actuated by the pawl.
18. In a continuous billing typewriting machine, the combination with a platen-displacing frame and a revoluble platen therein, of a tally-strip take-up roll on the platen-displacing frame, a hook for holding the platen-displacing frame in writing position, a handle for moving the hook to release the platen-frame, and mechanism operated by the movement of the handle to line-feed the take-up roll, comprising a line-space slide mounted on the machine-frame independently of the platen-displacing frame, a pawl carried by the line-space slide, and a ratchet-wheel fast to the take-up roll, latching means for holding the displacing frame down until the line-space slide has completed its operative movement, and means carried by the line-space slide to engage and move the latching means to release the latter at the conclusion of the operative movement of the line-space slide.
19. In a continuous billing typewriting machine, the combination with a traveling carriage, a platen-displacing frame and a revoluble platen therein, of a bracket on the displacing frame, a tally-strip take-up roll on the bracket, line-space mechanism for the take-up roll on the bracket, and legs extending downward from the bracket to engage the carriage to brace and support the bracket in the line-spacing of the take-up roll.
20. In a continuous billing typewriting machine, the combination with a revoluble platen and a carbon-carrier reciprocable toward and from the platen, of a work-web-supply holder mounted on the carbon-carrier for travel therewith.
21. In a typewriting machine, means for marking impressions upon a work-ply, a shield constructed to prevent the marking of impressions upon said work-ply, and a carrier for the shield to move the shield to and from its effective position.
22. A web-manifolding machine having a carriage, a displaceable platen-frame normally locked to the carriage, a record-web to be fed around the platen, a roll to wind up the delivery end of the record-web, and mechanism to jointly release the platen-frame and line-space the winding-up roll to feed the record-web.
23. In a typewriting machine for typing upon a plurality of work-plies and upon a record-ply, a cylindrical platen, a carbon-carrier to hold carbon interleaved between the work-plies, and a shield carried by the carbon-carrier to overlie a portion of the record-ply to prevent the marking of im-
- pressions thereon, said shield being adjustable to change its effective length according to the length of the carbon, the travel of the carbon-carrier, and the extent of the record-web area which it is desired to expose for receiving impressions.
24. In a typewriting machine, a platen, means for supplying a record-web and a carbon-web to print thereon, a shield interposed between the record-web and its carbon-web, and arranged to be line-fed therewith, a carrier for the shield advanceable with the shield at line-feeding, and means for moving the carrier to retract the shield below the line of writing from time to time to make the shield ineffective.
25. In a continuous billing typewriting machine, the combination with a cylindrical platen, of a carbon-carrier reciprocable toward and from the platen, and means on the carbon-carrier to yieldingly grip a record-web to the carbon-carrier, the arrangement being such that the record-web may be retracted by the retraction of the carbon-carrier, except when the record-web is held against retracting movement.
26. In a continuous billing typewriting machine, the combination with a cylindrical platen, of a carbon-carrier reciprocable toward and from the platen, a slotted bar on the carbon-carrier for guiding a record-web to a selected field of the platen, and means on the carbon-carrier to yieldingly grip the record-web to the carbon-carrier, the arrangement being such that the record-web may be retracted by the retraction of the carbon-carrier, except when the record-web is held against retracting movement.
27. In a continuous billing typewriting machine, the combination with a cylindrical platen, of a carbon-carrier reciprocable toward and from the platen, and a record-web-guide bar detachably mounted on the carbon-carrier, said bar having a slot through which the record-web may be passed, the arrangement being such that the ends of the slot may engage the opposite edges of the record-web to guide it to a selected field of the platen.
28. In a continuous billing typewriting machine, the combination with a cylindrical platen, of a carbon-carrier reciprocable toward and from the platen, and means on the carbon-carrier to yieldingly grip a record-web to the carbon-carrier, comprising resilient bars extending inward from opposite sides of the carbon-carrier, one above the other, and members on one of the bars to bear against the record-web and yieldingly secure it to the carbon-carrier, the arrangement being such that the record-web may be retracted by the retraction of the carbon-carrier, except when the record-web is held against retracting movement.
29. In a continuous billing typewriting

machine, the combination with a cylindrical platen, of a carbon-carrier reciprocable toward and from the platen, record-web-shielding means comprising a shield to extend between the record-web and its carbon to prevent the printing through on the record-web of a portion of the matter typed on an outside web, and a shield-carrying bar on the carbon-carrier, and means for yieldingly gripping the record-web to the carbon-carrier, including the shield-carrying bar, and a co-operating bar provided with rubber feet to engage the record-web, the arrangement being such that the record-web is retracted by retraction of the carbon-carrier, except when the record-web is held against retracting movement.

30. In a typewriting machine, a cylindrical platen, and means for guiding a work-web to a selected field of the platen, consisting of a slotted bar through which the work-web may be passed, the arrangement being such that the opposite side edges of the work-web are guided by the ends of the 25 slot.

31. A web-manifolding machine including a carriage, a displaceable platen-frame on the carriage, a record-web to be fed around the platen, a receiving roll for the delivery 30 end of the record-web, means for line-spacing the roll, and mechanism to prevent the displacement of the platen-frame until a complete line-spacing movement of said roll has taken place.

32. In a typewriting machine, the combination of a carriage, a swing-frame on said carriage, a platen carried by said swing-frame, a roll to wind up a sheet thereon to feed it around said platen, said roll being 40 supported on said frame, and means on said carriage to actuate said roll to rotate the latter.

33. In a typewriting machine, the combination of a carriage, a swing-frame on said 45 carriage, a platen carried by said swing-frame, a roll to wind up a sheet thereon to feed it around said platen, said roll being supported on said frame, a line-space wheel secured to said roll, and co-operating means 50 on said carriage to engage said wheel to rotate said roll to feed said sheet around said platen, the relation between said wheel and said co-operating means being such as to allow the wheel to be swung away from 55 the co-operating means when the swing-frame is operated.

34. In a typewriting machine, the combination of a carriage, a swing-frame on said carriage, a platen carried by said swing-frame, a roll to wind up a sheet thereon to feed it around said platen, said roll being 60 supported on said frame, a line-space wheel secured to said roll, means including a pawl on the carriage to engage said wheel, and a 65 finger-piece to actuate said pawl to rotate

said wheel and the roll connected thereto to feed the work-sheet around said platen.

35. In a typewriting machine, the combination of a carriage, a swing-frame on said carriage, a platen carried by said swing-frame, a roll to wind up a sheet thereon to feed it around said platen, said roll being supported on said frame, a line-space wheel secured to said roll, means including a pawl on the carriage to engage said wheel, and a finger-piece to actuate said pawl to rotate said wheel and the roll connected thereto to feed the work-sheet around said platen, the arrangement between the pawl and said wheel being such as to enable the wheel to be freely swung away from said pawl when the swing-frame is operated. 70 75 80

36. In a typewriting machine, the combination of a carriage, a swing-frame on said carriage, a platen carried by said swing-frame, a roll to wind up a sheet thereon to feed it around said platen, said roll being supported on said frame, a ratchet-wheel secured to said roll, a bracket on said carriage, a slide on said bracket, a pawl on said slide to engage said ratchet-wheel, and means including a finger-piece to actuate said slide to rotate said roll to feed said sheet around 85 90 95 said platen.

37. In a typewriting machine, the combination of a carriage, a swing-frame on said carriage, a platen carried by said swing-frame, a roll to wind up a sheet thereon to feed it around said platen, said roll being supported on said swing-frame, a delivery roll on said carriage, and means to rotate the winding roll to feed the sheet around 100 said platen.

38. In a typewriting machine, the combination of a carriage, a swing-frame on said carriage, a platen carried by said swing-frame, a roll to wind up a sheet thereon to feed it around said platen, said roll being supported on said swing-frame, a delivery roll on said carriage, means to unroll the sheet from said delivery roll, and means to rotate the winding roll to feed said sheet around said platen. 105 110

39. In a typewriting machine, the combination of a carriage, a swing-frame on said carriage, a platen carried by said swing-frame, a roll to wind up a sheet thereon to feed it around said platen, said roll being supported on said frame, a delivery roll on said carriage, an extension on said carriage, a reciprocable device on said extension to unroll the sheet from the delivery roll, and means to rotate the winding roll to feed said sheet around said platen. 115 120

40. In a typewriting machine, the combination of a carriage, a revoluble platen on said carriage around which a continuous sheet may be fed with a record-sheet, a supply-roll for said record-sheet at the introductory side of said platen, a reciprocable 125 130

device on said carriage to unroll said record-sheet from the supply-roll, a take-up roll at the delivery side of said platen for said record-sheet, and means to rotate said take-up 5 roll to feed said record-sheet around said platen.

41. In a typewriting machine, the combination of a carriage, a revoluble platen on said carriage around which a continuous 10 sheet may be fed with a record-sheet, a supply-roll for said record-sheet at the introductory side of said platen, an extension on said carriage, a reciprocable device on said extension, the supply-roll being supported 15 by said device so that the record-sheet may be unrolled from the supply-roll by an actuation of said device, a take-up roll at the delivery side of said platen, and means to rotate said take-up roll to feed the record- 20 sheet around said platen.

42. In a typewriting machine, the combination of a carriage, a revoluble platen on said carriage, a supply-roll on said carriage for a work-sheet conducted around said 25 platen, a swing-frame to support said platen, said swing-frame being pivoted on said carriage, and a take-up roll for said work-sheet, said take-up roll being located at the delivery side of said platen and sup- 30 ported by said swing-frame.

43. In a continuous billing typewriting machine, the combination of a cylindrical platen around which a composite web comprising separate plies of work-sheets may 35 be fed with interleaved carbon-sheets, a table at the introductory side of the platen, a carbon-carrier to which the carbon-sheets are attached on said table, means to condition the web to facilitate a shifting of the 40 carbon-sheets to a fresh portion of the web, the carbon-sheets being shiftable by said carbon-carrier, and a record-sheet supply-roll at the introductory side of the platen, said carbon-carrier being effective during 45 the shifting of the carbon-sheets to unroll the record-sheet from said supply-roll.

44. In a continuous billing typewriting machine, the combination of a cylindrical platen around which a composite web comprising separate plies of work-sheets may 50 be fed with interleaved carbon-sheets, a table at the introductory side of the platen, a carbon-carrier to which the carbon-sheets are attached on said table, means to condition the web to facilitate a shifting of the carbon-sheets to a fresh portion of the web, the carbon-sheets being shiftable by said carbon-carrier, and a record-sheet supply-roll mounted on said carbon-carrier to be carried 55 with said carbon-carrier during the carbon-shifting operation to unroll the record-sheet 60

45. In a typewriting machine, the combination of a traveling carriage, a carbon-carrier mounted to travel with said carriage,

said carbon-carrier being shiftable to shift 65 a carbon-sheet to a fresh portion of a continuous work-sheet, and a work-sheet supply-roll mounted on said carbon-carrier.

46. In a typewriting machine, the combination of a traveling carriage, a carbon-carrier 70 mounted to travel with said carriage, said carbon-carrier being shiftable to shift a carbon-sheet to a fresh portion of a continuous work-sheet, and a work-sheet supply-roll mounted on said carbon-carrier which 75 may be unrolled by a movement of said carbon-carrier.

47. In a typewriting machine, the combination of a traveling carriage, a platen on 80 said carriage, a table to travel with said carriage, a carbon-carrier mounted on said table to travel therewith, said carbon-carrier being shiftable to shift a carbon-sheet to a fresh portion of a work-sheet, and a work-sheet supply-roll mounted on said carbon- 85 carrier which may be unrolled by a movement of said carbon-carrier on said table and in a direction away from said platen.

48. In a continuous billing typewriting machine, the combination of a cylindrical 90 platen around which a composite web comprising separate plies of work-sheets may be fed with interleaved carbon-sheets, a table at the introductory side of the platen, a carbon-carrier to which the carbon-sheets 95 are attached on said table, means to condition the web to facilitate a shifting of the carbon-sheets to a fresh portion of the web, the carbon-sheets being shiftable by said carbon-carrier, a record-sheet supply-roll at 100 the introductory side of the platen, said carbon-carrier being effective during the shifting of the carbon-sheets to unroll the record-sheet from said supply-roll, a receiving roll at the delivery side of the platen, and means 105 to rotate said receiving roll to feed the record-sheet around said platen.

49. In a continuous billing typewriting machine, the combination of a cylindrical 110 platen around which a composite web comprising several plies of work-sheets may be fed with interleaved carbon-sheets, a table at the introductory side of the platen, a carbon-carrier to which the carbon-sheets are attached on said table, a swing-frame to support the platen by which it may be swung to an abnormal position to facilitate a shifting of the carbon-sheets to a fresh portion of the web, the carbon-sheets being shiftable by said carbon-carrier, a record-sheet 120 supply-roll at the introductory side of the platen, said carbon-carrier being effective during the shifting of the carbon-sheets to unroll the record-sheet from the supply-roll, a receiving roll at the delivery side of the 125 platen, a finger-piece to release said swing-frame to enable the platen to be swung to said abnormal position, and means actuatable

by said finger-piece to rotate said receiving roll to feed the record-sheet around said platen.

50. In a continuous billing typewriting machine, the combination of a platen around which a work-sheet and a record-sheet may be fed with an interleaved carbon-sheet, a swing-frame to support said platen and by which the platen may be swung to an abnormal position to release the sheets, so that the carbon-sheet may be shifted relatively thereto, a table on said swing-frame at the delivery side of the platen, a receiving roll for the record-sheet, said receiving roll being supported behind said table, said table having a slot therein through which the record-sheet may be conducted from the front of the table to the rear thereof and then to the receiving roll, said table having an opening in the front thereof, and a gage for the work-sheet, said gage being adjustable in the opening of said table.

51. In a web-manifolding machine having a carriage, a displaceable platen-frame on the carriage and a reciprocable carbon-carrier to strip carbon from the main webs, the combination of a record-web-winding roll, a record-web-supply roll mounted upon said carrier, line-spacing mechanism feeding the main webs and record-web around the platen and operating to produce a slack

in the typed record-web at the delivery side of the platen between the same and said winding roll, and other means for operating said winding roll.

52. In a web-manifolding machine having a platen and a carriage, a displaceable platen-frame on the carriage and a reciprocable carbon-carrier to strip carbon from the main work-webs, the combination of a record-web-supply roll mounted upon said carbon-carrier, and a record-web-winding roll mounted on said displaceable platen-frame, whereby a slack is produced in the record-web between the two rolls at the displacement of the platen-frame.

53. In a web-manifolding machine having a platen and a carriage, a displaceable platen-frame on the carriage and a reciprocable carbon-carrier to strip carbon from the main work-webs, the combination of a record-web-supply roll mounted on said carbon-carrier, and a record-web-winding roll mounted on said displaceable platen-frame, whereby a slack is produced in the record-web between the two rolls at the displacement of the platen-frame and the tension of the retracted webs is not disturbed during the replacement of the platen-frame to operative position.

JESSE A. B. SMITH.
